(57) **CLAIM**

The ornamental design for an earphones with charging case assembly, as shown and described.

DESCRIPTION

FIG. 1 is a perspective view of a charging case of an earphones with charging case assembly shown separately to show aspects of the design that are not visible when combined and in an open state, showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged perspective view of an earphones of the earphones with charging case assembly shown separately to show aspects of the design that are not visible when combined;

FIG. 11 is another perspective view thereof;

FIG. 12 is a front side elevational view thereof;

FIG. 13 is a rear side elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is a perspective view of the earphones with charging case assembly, shown in an open configuration; and,

FIG. 19 is another perspective view of the earphones with charging case assembly, shown in a closed configuration.

The dash-dash broken lines in the drawings depict portions of the earphones with charging case assembly that form no part of the claimed design.

1 Claim, 19 Drawing Sheets
